UNITED STATES PATENT OFFICE

2,493,073

METHOD OF VAPORIZING OR GASIFYING LIQUIDS

William Patrick Kinneen, Dublin, Eire

Application August 10, 1946, Serial No. 689,766
In Great Britain August 14, 1945

3 Claims. (Cl. 219—40)

1

This invention relates to an improved method of vapourising or gasifying liquids, more particularly liquids which it is desired to vapourise or gasify in order to produce the driving gases of jet-propulsion units or internal combustion engines, although it is generally applicable to the vapourising or gasifying of liquids for any purpose, subject only to the limitation that a jet of the liquid in question shall be capable of conducting an electric current.

According to the present invention, a jet of the liquid to be vapourised or gasified is forced through a nozzle on to a conductive surface or electrode and an electric current of sufficient intensity to vapourise or gasify the liquid is passed through the jet.

This may conveniently be done by making the nozzle, through which the jet is forced, of metal and by establishing a suitable potential difference between the nozzle and the surface or electrode on which the jet impinges. The potential difference and the intensity of the current flowing through the jet will, of course, vary according to the nature of the liquid (or mixture of liquids) forming the jet.

In order that this invention may be the more clearly understood and readily carried into effect, I will proceed to describe the same with reference to the accompanying drawings, which illustrate by way of example certain embodiments of this invention, and in which:

Figure 1 is a somewhat diagrammatic section through a single jet gasifying heat generator and part of a gas expansion chamber according to the present invention.

Figure 2 illustrates a two jet system according to the present invention.

Figures 3 and 4 illustrate embodiments of the present invention using a two and three phase source of electric supply for the vapourisation of liquids from two and three jets respectively.

Referring now more particularly to Figure 1 of the drawings, the body of the apparatus may be made as a unit and comprises a gasifying head 10 leading directly to a gas expansion chamber 11.

The head 10 is provided with one or more nozzles 12 passing through the walls, the fitting of the nozzle, or each of the nozzles, as the case may be, being of such a nature as to prevent the escape of gas. For simplicity of description it will be assumed in the following description that only a single nozzle 12 is employed. The nozzle 12 is supplied with the liquid to be gasified under pressure through the pipe 13 and non-return valve 14.

5 The pressure on the liquid may be obtained by means of a pump, by means of air pressure within the storage tank for the liquid, or by gravity. The non-return valve 14 is provided in order to prevent the back pressure of the gases formed in the head affecting the supply of liquid to the nozzle and, in some cases, is unnecessary.

10 The body of the gasifying head and the nozzle 12 are in electrical connection with one another and are connected to an "earthed" terminal of a source of electric power shown diagrammatically in Figure 1 as a battery 15. It may not be necessary actually to earth the body of the gasifying head but it can be considered as the ground potential of the whole apparatus.

15 Inserted through the wall of the head 10 and insulated therefrom by any insulating sleeve is an electrode 17, this electrode projecting inwardly, as shown, and being positioned immediately opposite the nozzle 12. The spacing between the electrode 17 and the nozzle 12 may, if desired, be adjustable.

20 The electrode 17 is connected electrically to a suitable potential on the battery or source of supply 15 so that the jet of liquid issuing from the nozzle 12, which will strike and contact electrically the projecting electrode, will carry an electric current of sufficient intensity to vapourise the liquid into a gas.

25 As above stated, more than one nozzle 12 with the corresponding number of co-operating electrodes 17 may be provided in the gasifying head. These nozzles may all be supplied with the same liquid, or may be supplied with different liquids which are gasified and mixed within the gasifying head. Where different liquids are supplied to the nozzles, it may be desirable to establish different potential differences across the jets. This may be done by returning the different electrodes 17, 17a to different points on the battery or source of power 15, as shown in Figure 2, the nozzles 12, 12a being grounded to the common point of the supply.

30 Where the gasifying head employs two jets or two groups of jets, the jets being of the same or different liquids, it is convenient to employ a two-phase system of electrical supply, as shown diagrammatically in Figure 2. All the nozzles 12 are connected to the electrical centre of the two phase system 20. One electrode or set of electrodes 17 is connected to one of the phases, and the other electrode or set of electrodes 17a is connected to the other phase, both at potentials suitable for the liquid or liquids being used. The positioning of the nozzles and electrodes in the gasifying head

may be such that, when splash of liquid takes place, there can be a flash-over from the greater voltage between the phases at the electrodes, thereby causing better gasifying action.

In a similar manner to that of using a two-phase supply system, a three-phase supply may be used, as shown in Figure 4. All the nozzles are connected to the electrical centre of the supply system and the individual electrodes, or groups of electrodes, are connected to the phases as shown at potentials suitable to the liquids being used.

In some cases, air or other gas or gases may be injected into the gasifying head or gas expansion chamber to assist the gasifying action. Thus, as shown in Figure 1, air or other gas may be injected into the gasifying head 10 through a pipe 30 and non-return valve 31.

The form of the gas expansion chamber 11 will depend upon the use for which the apparatus is intended. For example, it may have an open end where the apparatus is to be used as a jet propulsion engine. Alternatively, it may be closed and provided with gas outlets to feed a turbine or a reciprocating engine. In this case, a non-return valve is preferably provided in the base of the gas expansion chamber leading to a run-off pipe through which any liquid not vapourised is automatically ejected.

A further possibility is to fit the gasifying head to the induction manifold or cylinder block head of an internal combustion engine, the cylinders of the engine serving as the gas expansion chamber. In this case, the supply of liquid to the gasifying head may be controlled in a manner similar to that of a Diesel or semi-Diesel engine, liquid being fed to the nozzle only when the compression of the air inducted is about its maximum.

I claim:

1. Apparatus for vapourising or gasifying a liquid capable of conducting an electric current by passing an electric current of sufficient intensity to vapourise or gasify the liquid through the same comprising a gasifying head including at least one tubular nozzle of conducting material to which the liquid to be gasified is fed, and at least one electrode disposed opposite said nozzle, together with means for establishing a sufficient potential difference between said nozzle and said electrode.

2. Apparatus according to claim 1, in which the liquid is fed to said nozzle through a non-return valve.

3. Apparatus according to claim 1, including means for feeding a gas to the gasifying head through a non-return valve.

WILLIAM PATRICK KINNEEN.
